UNITED STATES PATENT OFFICE.

JUDIE PARDEE MITCHELL, OF DENVER, COLORADO.

DESIGN FOR A RADIATOR CAP.

Application filed February 1, 1927. Serial No. 20,570. Term of patent 7 years.

To all whom it may concern:

Be it known that I, JUDIE PARDEE MITCHELL, a citizen of the United States, residing at the city and county of Denver and State of Colorado, have invented a new, original, and ornamental Design for Radiator Caps, of which the following is a specification, reference being had to the accompanying drawings, forming part thereof.

The figure is a perspective view of the rear and also of the front side of my new design, as the design is identical on both sides.

I claim:

The ornamental design for a radiator cap, as shown.

In testimony whereof I affix my signature.

JUDIE PARDEE MITCHELL.
